UNITED STATES PATENT OFFICE.

FREDERICK KAMPFE, OF NEW YORK, N. Y.

DESIGN FOR AN ADVERTISING DEVICE.

SPECIFICATION forming part of Design No. 35,047, dated September 3, 1901.

Application filed July 27, 1901. Serial No. 69,995. Term of patent 7 years.

To all whom it may concern:

Be it known that I, FREDERICK KAMPFE, a citizen of the United States, residing in New York, borough of Manhattan, in the State of New York, have invented and produced a new and original Design for Advertising Devices, of which the following is a specification.

As shown in the accompanying drawing, the design consists of a base *a*, pedestals *b*, supported on said base, and upright columns *c*, supported on said pedestals and provided at the top with ball-shaped terminals or caps *d*. The columns are connected by a transverse bar *e*, having acorn-shaped terminals *e'*. An oblong panel *f* is suspended by chains from said bar *e* and an arc-shaped panel *h* sup-

ported on the bar. Centrally surmounted on the base is a pyramidal portion formed integral therewith and representing in appearance a pile of boxes *i*, the bottom boxes being 20 slightly spaced apart.

I claim as new and desire to secure by Letters Patent—

The design for an advertising device, as herein shown and described. 25

In testimony that I claim the foregoing as my invention I have signed my name in presence of two subscribing witnesses.

FREDERICK KAMPFE.

Witnesses:

PAUL GOEPEL,
JOSEPH H. NILES.
